Richard Skinner, Williamson & Co.

Seller's Patent.

The belleville referred to in these Seller's Patent documents is a part of the same, containing a description in the words of the said Richard Skinner himself of his improvement in horse power for threshing machines.

To all persons to whom these presents shall come; Richard Skinner of the town of Williamson in the County of Wayne and state of New York sends greeting: Be it known that the said Richard Skinner has invented a new and useful improvement not known or used before in the making of horse power for threshing machinery which invention and the manner of using it is as follows: The improvement invented is a hub and a retainer for the main wheel instead of the shaft and journal or guides in commerce used with sleeves or bars fastened to the hub and to the ring of the main wheel; also a pinion cast in the form of a pipe with a sufficient length to unite with the hub on the main wheel the band wheel to be fastened to the pinion. The pinion and hub being on each side attached that are made fast in the formation or bed pinion the with pinion whereof I have herewith described my name the 12th day of February in the year 1836.
